US0D1111802S

(12) **United States Design Patent** (10) **Patent No.:** **US D1,111,802 S**
(45) **Date of Patent:** **** Feb. 10, 2026**

(54) **SELF-LOCKING CONNECTOR**

(71) Applicant: **ZHONGSHAN WOSIGN ELECTRIC TECHNOLOGY CO., LTD.**
Zhongshan (CN)

(72) Inventor: **Desheng Wang**, Shenzhen (CN)

(***) Term: **15 Years**

(21) Appl. No.: **29/797,053**

(22) Filed: **Jun. 29, 2021**

(51) LOC (15) Cl. **08-08**

(52) U.S. Cl.

USPC **D8/382**

(58) **Field of Classification Search**

USPC D8/349, 354, 382

CPC F16B 9/052; F16M 13/02

See application file for complete search history.

(57) **CLAIM**

The ornamental design for a self-locking connector as shown and described.

DESCRIPTION

FIG. 1 is a perspective view of a self-locking connector showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the self-locking connector that form no part of the claimed design.
